UNITED STATES PATENT OFFICE.

CHARLES C. ISHAM, OF CINCINNATI, OHIO.

DESIGN FOR A HAT-RACK.

SPECIFICATION forming part of Design No. 13,480, dated December 19, 1882.

Application filed August 7, 1882. Term of patent 7 years.

To all whom it may concern:

Be it known that I, CHARLES C. ISHAM, a citizen of the United States, residing at Cincinnati, in the county of Hamilton and State 5 of Ohio, have invented and produced a new and original Design for Hat-Racks, of which the following is a specification, reference being had to the accompanying photograph, forming a part hereof, which is taken in perspective.

10 The main feature of my design is the well-known square and compass, the latter placed above or under the former, the space left in the center being occupied by a diamond-shaped mirror. A series of pins or hooks are placed 15 at proper points, as shown, on which may be suspended articles of wearing-apparel, such as hats, coats, &c.

A hat-rack made in this design may be jointed and hinged at certain points, so the 20 same may be easily folded into a small space for convenience in shipping. It may, however, also be constructed in one piece when so de-

sired. The compass-shaped part of the rack supplies the supporting-legs. The "square" is provided with the pegs which sustain the 25 weight of the hats, coats, and other articles of apparel. The mirror is of diamond shape and secured at two of its corners to the inner sides of the compass-legs.

The photograph hereto annexed represents 30 ordinary turned pins placed at convenient points; but hat or coat hooks of any suitable shape or design may be used instead.

Having thus described my new design in hat-racks, what I claim as new is— 35

The design for a hat-rack herein shown and described, consisting of an open compass and square, and a diamond-shaped mirror arranged in the space between them and attached to the compass-legs, substantially as set forth.

CHAS. C. ISHAM.

Attest:

J. F. BALDWIN,
E. J. HOWARD.
